RIDE CAR LIFT TOWER

Alan B. Hawes, 8504 Seaview Ave.,
Wildwood Crest, N.J. 08260

Filed Aug. 12, 1966, Ser. No. 3,440

Term of patent 14 years

(Cl. D13—1)

FIG. 3.

I claim:

The ornamental design for a ride car lift tower, as shown.
